CLAIM

(21) Appl. No.: **29/294,996**

The ornamental design for a shroud for portable gas cylinder, as shown and described.

(22) Filed: **Feb. 6, 2008**

DESCRIPTION

(51) **LOC (8) Cl.** 23-01

FIG. 1 is a perspective view of the shroud for portable gas cylinder showing our new design;

(52) **U.S. Cl.** D23/206

FIG. 2 is a front view thereof;

(58) **Field of Classification Search** D23/202,

FIG. 3 is a side view thereof; and,

D23/206, 225; 220/581; 206/0.6

FIG. 4 is a top view thereof.

See application file for complete search history.

The broken line showing of the gas cylinder is included for the purpose of illustrating and forms no part of the claimed design.
